UNITED STATES PATENT OFFICE.

CHARLES WINK, OF POMEROY, OHIO.

SCOW.

SPECIFICATION forming part of Letters Patent No. 690,216, dated December 31, 1901.

Application filed September 9, 1901. Serial No. 74,864. (No model.)

To all whom it may concern:

Be it known that I, CHARLES WINK, a citizen of the United States, residing at Pomeroy, in the county of Meigs and State of Ohio, have 5 invented certain new and useful Improvements in Scows, &c.; and I do declare the following to be a full, clear, and exact description of the invention, such as will enable others skilled in the art to which it appertains to make 10 and use the same, reference being had to the accompanying drawings, and to the figures of reference marked thereon, which form a part of this specification.

My invention relates to improvements in 15 the construction of barges, scows, and other vessels, and more particularly to the method of securing the floor-timbers to the hull. They are at present dovetailed and sunk into the hull of the vessel, thus making it necessary 20 to cut a recess in the hull larger than the end of the floor-timber and then wedging the floor-timber into it. This weakens the hull, and if it becomes necessary to remove the floor-timber it can only be done by cutting away 25 several inches of the hull, thus weakening it still more. To overcome this objection, I provide a dovetailed socket or holder, which is secured to the hull and in which the ends of the floor-timbers are supported.

30 The invention will be more clearly understood from the detailed description hereinafter and the appended claims.

In the accompanying drawings, Figure 1 is 35 a plan view of the scow, the flooring being removed. Fig. 2 is a section on the line 2 2 of Fig. 1. Fig. 3 is a detail view in elevation of the socket or holder. Fig. 4 is a section on the line 4 4 of Fig. 3, and Fig. 5 is a section on the line 5 5 of Fig. 3.

40 Referring to the drawings, 6 denotes the hull or gunwale of a scow, and 7 the floor-timbers. The device for supporting the floor-timbers is indicated at 8 and comprises a plate 9, which is securely fastened to the hull or 45 gunwale by screws 9^a or otherwise. Projecting from said plate 9 are two arms or projections 10 and 10^a, one of them or both being beveled, as indicated at 10^b, forming a dovetailed socket or recess into which the floor-timber is fitted, the ends of the same being 50 previously shaped to correspond to the shape of the socket or recess. To prevent upward movement of the floor-timbers, I provide a

recess or key-seat 11 in the projection 10 and 10^a, into which the key 12 is inserted. 55 This key is preferably made of metal and has an aperture 12^a, through which a spike 12^b is driven into the floor-timbers, thus securely holding all the parts together.

When it becomes necessary on account of 60 rotting or breaking of the floor-timbers or from any other cause to remove the same, it can be done by merely withdrawing the key and lifting said floor-timbers out of the socket or holder and placing new ones in position. 65

These holders may be constructed of cast-iron and made in different sizes to fit the ends of different-sized floor-timbers, each end of each floor-timber resting in one of the holders in such a manner that when the key is 70 placed in position the floor-timbers will remain in position and cannot move. The use of this holder also saves one foot in the length of each floor-timber.

Having thus described the invention, what 75 I claim as new, and desire to secure by Letters Patent, is—

1. In a scow or other vessel means for securing the floor-timbers to the hull, comprising a plate secured to the hull, a socket in 80 said plate adapted to receive the floor-timbers, a key-seat in the socket and a key in said key-seat.

2. In a scow or other vessel, means for securing the floor-timbers to the hull, comprising a plate secured to the hull, a dovetailed socket in said plate adapted to receive the floor-timbers, a key-seat in the socket, and a key in said key-seat. 85

3. In a scow or other vessel, means for securing the floor-timbers to the hull, comprising a plate secured to the hull, arms extending from said plate adapted to hold the floor-timbers, a recess in said arms, and a key adapted to enter said recess. 90

4. In a scow or other vessel, means for securing the floor-timbers to the hull, comprising a plate secured to the hull, arms extending from said plate forming a dovetailed recess adapted to receive the floor-timbers, a 100 key-seat in said arms, and a key in the key-seat.

CHARLES WINK.
